CASSETTE

Wayne C. Hunt, Chicago, Ill., assignor of forty
per cent to G. G. G. Peckham, Shaker Heights,
Ohio

Application December 8, 1931, Serial No. 579,678

1 Claim. (Cl. 250—34)

This invention relates to improvements in cassettes or holders for sensitized films and intensifiers used in connection with X-ray apparatus.

One of the principal objects is to provide a cassette which may be manipulated for insertion and removal of the films and intensifiers by the use of only one hand. A further object is to provide such a device which can be so operated in a shorter time and with less effort. A further object is to provide a lighter device of this type without any sacrifice of rigidity. A further object is to provide novel means for the prevention of fogging of the plates by "back scattering" or secondary radiation.

I attain the foregoing and other and more limited objects, as will appear, in and through the construction hereinafter described and illustrated in the accompanying drawings in which Fig. 1 is an elevation of the back of the cassette showing the improved locking means in the position it takes when the cassette is locked; Fig. 2 is a central longitudinal section showing the locking means in unlocked position; Fig. 3 is a fragmentary sectional view showing a modified form; and Fig. 4 is a section on line 4—4 of Fig. 1.

Referring now to the accompanying drawings, the numeral 10 indicates a frame of rectangular shape composed of a bar of steel tubing bent to shape and welded or otherwise secured to form a rigid unit and being preferably although not necessarily rectangular in cross section. Secured to the frame 10 is a window or front 11 composed of a material of such tensile strength and rigidity as to prevent bulging under applied pressure and having the quality of being readily pervious to X-rays. For this purpose I prefer to employ one of the synthetic resins, such as bakelite. The window 11 may be secured 40 to the frame 10 as by a plurality of screws 12. Within the frame 10 and secured to the inner face of the window 11, I provide a sheet of felt or similar material 13. At the central part of each of the sides of the frame 10 I provide milled slots 14. In one of the side members I provide slots 15 for reception of hinged knobs 16 carried by hinge members 17. The hinges 17 are secured as by screws to the back 18 of the cassette. On the inside of the back 18 is a sprayed coating 50 of lead 19 and a layer of felt 20, while on the outside is a locking means and control therefor adapted to cooperate with the slots 14 in the frame 10. The sprayed coating of lead serves to prevent fogging of the films due to back scattering, while the layer of felt 20 cooperates with

a similar layer 13 to hold the X-ray film 21 and intensifier if used.

A plurality of slides 22 are slidably secured to the back 18 as by studs 23 extending through slots 24 therein. These slots may be continuous, as shown, or individual to each of the studs, although it is preferred to use the construction illustrated. At the end of each of the slides adjacent the frame member with which it is related is an upwardly curved portion 25 adapted to enter the corresponding slot 14 for the purpose of urging the back 18 into film holding contact. The opposite end of each of the members 22 is formed into a hinge element 26 which cooperates with a pintle 27 and a corresponding hinge element on the corresponding link 28. Each of the links 28 is hingedly connected with the central member 29, as indicated at 30. Between the hinge connections 30 the edge of the member 29 is preferably turned up, as shown at 31, or rounded off to assist the operator in grasping it. The back 18 may also be cut away through a portion of its depth adjacent the parts 31 to provide finger openings 32. A tab 33 may be secured similarly to the member 29 for grasping.

In the modification shown in Fig. 3, the sliding member 22 is allowed to contact the back 18 by reason of the countersinking of the collar 23a into the back 18, as shown. In other respects this modification is identical with that illustrated in the other figures.

It is an important feature of my invention that the degree of pressure can be determined and made uniform by the height of the up-curved portions 25 which engage in the slots 14. The use of square metallic tubing for the frame members is especially adaptable to this purpose, it being only necessary to provide the slot 14 extending completely to the upper wall of the tubing, as shown. Should it happen that too much metal were cut away from the upper edge of the inner wall in the process of milling the slots 14, the accuracy would not be impaired because the member 25 would extend far enough into the tube to engage the inner surface of the upper wall. Furthermore, the use of the square metallic tubing for the frame members 10 results in considerable reduction in weight without loss of rigidity.

In operation, the cassette just described may be both unlocked and opened about the hinges by the same operation, namely, grasping the member 29 or tab 33 and pulling upwardly. Such operation results first in withdrawal of the slides 22 to the position shown in Fig. 2 and

then by the same motion in hinging of the back 18 about the member 16. The closing operation likewise can be performed with one hand; and a single operation suffices both to close the back 5 and lock the same in proper position.

Having thus described my invention, what I claim is:

In a cassette, a frame, a window secured thereto, a back hingedly connected therewith, adapted 10 to be received therein and carrying latching means adapted to cooperate with said frame for

holding such back in position with respect thereto and pressing the same toward said window, a single control means for operating said latches and moving said back about its hinges, said control means comprising mechanism whereby a 5 continuous motion of a single element without abrupt change in direction results in unlatching the latching means and moving said back about its hinges or moving said back to closed position and latching said latching means. 10

WAYNE C. HUNT.
